United States Patent Office

Des. 228,051
Patented Aug. 7, 1973

228,051

STUDY CARREL

Calvin Masaru Shimaoka, Harbor City, and Anton A. Sixt, Laguna Hills, Calif., assignors to Carter Industries, Inc., Santa Ana, Calif.

Filed Dec. 3, 1971, Ser. No. 204,785

Term of patent 14 years

Int. Cl. D6—04

U.S. Cl. D6—181

FIG. 2

FIG. 3

FIG. 4

FIG. 5

FIG. 6.

FIG. 7.

FIG. 8.

FIG. 9.

FIG. 10.

FIG. 1 is a perspective view of a study carrel showing our new design;

FIG. 2 is a side elevational view;

FIG. 3 is a top plan view;

FIG. 4 is a rear elevational view;

FIG. 5 is a front elevational view;

FIG. 6 is a perspective view of a modified form of a study carrel showing our new design;

FIG. 7 is a side elevational view thereof;

FIG. 8 is a top plan view;

FIG. 9 is a rear elevational view; and

FIG. 10 is a front elevational view.

We claim:

The ornamental design for a study carrel, substantially as shown and described.
